A. C. FISCHER

ELASTIC AND EXPANSIBLE PAVING JOINT

Filed July 3, 1920

UNITED STATES PATENT OFFICE.

ALBERT C. FISCHER, OF CHICAGO, ILLINOIS.

ELASTIC AND EXPANSIBLE PAVING JOINT.

Application filed July 3, 1920. Serial No. 393,801.

REISSUED

To all whom it may concern:

Be it known that I, ALBERT C. FISCHER, a citizen of the United States, residing at Chicago, in the county of Cook and State 5 of Illinois, have invented certain new and useful Improvements in Elastic and Expansible Paving Joints, of which the following is a specification.

My invention relates to improvements in 10 means permitting expansion and compensating for contraction of street paving. Heretofore it has been the practice to use, between sections of paving, an asphaltic filler or one built up in layers of asphaltic material 15 placed between layers of saturated felt, or a mastic body of felt compounded and saturated with a waterproofing material which was constructed in slabs or board-like strips, to be placed between bricks, curbs, 20 concrete blocks and other structural material.

One difficulty experienced in the use of 25 many of these expedients has been that when the strip is laid in the fall, or if through any chance frost finds its way under the strip, the strip will be raised, sometimes as much as several inches, and in some instances almost entirely expelled by the frost under the concrete. This is made possible 30 by the fact that when the concrete contracts the material of the joint does not expand to the width of the opening in which it was first inserted. The result is that considerable 35 of the material is lost and its purpose defeated. Moreover, the volatile oils with which the joint is saturated leave the waterproofing material, so that it deteriorates to a hard, brittle, and dried out condition and no longer has the elastic 40 effect which it had when first installed. Under such conditions the felt even deteriorates and rots, leaving a powdery substance in its place. This is due to the fact that the street often reaches a temperature as 45 high as 140 degrees at which considerable of the volatile oils in the asphaltic material necessarily evaporate; the felt being a great conserver of heat and the asphaltic material saturated therein holding heat considerably longer than the concrete or paving 50 material does. Another condition to be met is that when the concrete paving expands it often squeezes out the contents of the joint, and traffic wears it away until 55 the material which was originally used as a filler no longer fills up the space which

was at first occupied by the joint, and weather and elements are free to enter.

My invention consists in using an insulating material, such as mineral fibre, asbestos fibre, or the like, which is proof against street acids and rotting processes, saturated in a waxy or paraffinous waterproofing compound and thoroughly compressed into a block-like structure, preferably wedge shaped with the base of the wedge at the bottom of the strip, the upper part of the strip or slab being further immersed in an asphaltic waterproofing compound which gives it a solid but pliant consistency for 60 several inches downward from the top of the joint, leaving the base light in weight and composed only of the fibres coated and compressed with a waterproofing material, which is light in structure and yields by 65 compression to pressure from below instead of rising out of its seat, and thus remains in place under the adverse conditions of use. I thus create a joint which is less than half the weight of the solid joint as now being 70 placed upon the market, and more durable in use than such joint. My improved paving joint, under the conditions named, will wedge more tightly into place instead of 75 working out. It is constructed of material 80 which is resistant to temperatures of the hottest possible weather, and it provides a plastic asphaltic top to the joint which will close and seal the top of the joint space, 85 presents a wearing surface to the traffic, and, under pressure, will be pressed into the 90 crevice and adapt itself to the top opening thereof. Upon expansion of the concrete or paving material, the joint will not ooze out, but by reason of its insulating nature will 95 retain a non-fluid state.

In order that the invention may be fully understood, several embodiments thereof are disclosed, by way of illustration, in the accompanying drawings.

In said drawings:—

Figure 1 represents a joint packing of rectangular section made of fibrous material, with a crown thoroughly immersed in asphaltic material while hot, giving it a 105 tough wearing surface and sealing head.

Figure 2 shows a joint packing composed of fibrous material along the sides of a saturated piece of felt and with a crown of asphaltic fibrous material giving firmness 110 to the joint.

Figure 3 shows a joint packing compris-

ing built-up layers of dried fibrous material saturated with light waterproofing material and having a crown of heavy waterproofing.

Figure 4 shows a joint packing comprising an entire fibrous body immersed in a light waterproofing material, which does not add materially to its weight.

Figure 5 shows joint packing of wedge shaped section, having a crown of solid asphaltic matter which has been absorbed by the porous body of the fibrous matter.

Figure 6 shows a section with flaring base to prevent working up of the joint.

Figure 7 shows a joint packing having a double wedge section which prevents the working up of the joint without developing any overhang in the concrete or weakening the thickness of the paving on either side.

Figure 8 shows how wedge shaped joint packings may be packed without causing the bituminous matter on the crowns to adhere together.

Figure 9 shows a solid fibrous block entirely immersed in a solid asphalt while hot, giving to the block a tough, compact, fibrous consistency when cool.

Figure 10 shows concrete, brick, or block paving with joints embodying the subject-matter of the present invention disposed along the sides.

Figure 11 shows the joint between two construction surfaces and illustrates how the crown adapts itself to the top of the crevice, the resiliency of the base allowing the crown to spring down and lock with the pressure of the traffic, yet presenting a wearing surface to the traffic.

Figure 12 illustrates the form of Figure 7 in use; and

Figure 13 represents the form of Figure 5 in use.

In all of the figures, A represents the body of the packing which is made of asbestos, mineral wool, or equivalent light fibre, felted together and saturated with paraffin, or its equivalent, for the purposes hereinabove described. The body will be formed of a section suitable to fill the space between paving members X, Y, Figures 11, 12, and 13, of such thickness that it can yield to the approach of the paving members when they expand under heat, and of such inherent elasticity that it will expand and continue to fill the packing space even though the paving members draw apart under contraction. The body is also such that pressure exerted vertically upon it, from either below (as in case of frost) or above (as from traffic) will be absorbed in the inherent compressibility of the body instead of displacing the body.

The head or upper portion B is immersed in asphaltic material of such consistency as to provide a substantial pliable envelope,

and render the upper portion compressible and ductile to the extent of adapting itself to the packing opening, filling and sealing the same, and spreading out and presenting a resistant portion of the street surface under the traffic which it encounters.

The body preferably has its side lines so developed that it enlarges downwardly from some transverse line or lines in its section so as to present an enlargement that resists 70 expulsion of the packing under vertical pressure. This may be accomplished by making the wedging sections of Figures 5, 8, and 13, or the flaring lower end of Figure 6; and the taper may be developed from 75 both top and bottom toward the middle as shown in Figures 7 and 12 to resist vertical displacement in either direction. With the wedging lines, vertical pressure tends to 80 tighten the packing in its seat.

Under the pressure of traffic, the asphalt-enveloped head spreads as suggested in Figures 11, 12, and 13, seals the joint, and presents a tough wearing surface to traffic.

From the foregoing it will be seen that 85 the surface of my new joint will meet the unusual condition which is demanded of it, will always present a filling for the crevice, and will not be subject to the conditions that 90 a solid asphaltic or board-like felt joint is 95 subject to. While of fibrous nature, it is not subject to rotting process. The shape of the joint and its inherent structure save it from the fluid consistency which an asphaltic joint has.

I claim:

1. An expansion joint composed of compressible mineral fibrous matter having cells or pores, and having the upper portion thereof composed of a substantially solid 105 mass of asphaltic or bituminous substance penetrated into the fibrous structure and forming thereon a solid non-fluid head.

2. A packing for paving joints, composed of fibrous material coated with a relatively light waterproofing material which does not add materially to its weight, said coated 110 fibrous material being felted into a cellular mass.

3. A packing for paving joints, composed of fibrous material coated with a relatively light waterproofing material which does not add materially to its weight, said coated fibrous material being felted into a plurality 115 of layers of cellular structure, and said layers being assembled in the packing.

4. A packing for paving joints, comprising felted fibrous material built up in layers, immersed in a waterproofing material, and having a crown consisting of heavy asphaltic material.

5. A packing for paving joints comprising a heavy saturated felt with sides of lightly felted fibrous material, waterproofed and crowned with a solid asphaltic material.

6. A fibrous material waterproofed with a waterproofing substance which does not add materially to its weight, and having a crown of bituminous matter imparting a tough resilience to the crown.
7. A mineral fibrous matter lightly pressed into an air cell structure, adhered with a waxy or paraffinous waterproofing material which does not add materially to its weight.
8. A joint packing consisting of fibrous material formed into a light cellular structure, and having a portion thereof jacketed with a ductile substance that renders it tough and resilient.
9. A joint paving constructed of a compressible body of felted fibrous material adapted to enter between sections of paving and having its portion which is adjacent to the surface of the paving when in use, filled with asphaltic or bituminous substance which converts it into a substantially solid mass.

Signed at Chicago, Illinois, this 30th day of June, 1920.

ALBERT C. FISCHER.
